UNITED STATES PATENT OFFICE.

LE ROY A. CRUMLEY, OF NEW YORK, N. Y., ASSIGNOR TO THE ROGERS SILVER PLATE CO., A CORPORATION OF CONNECTICUT.

DESIGN FOR A LIGHTING-FIXTURE PART.

Application filed March 24, 1924. Serial No. 9,051. Term of patent 7 years.

To all whom it may concern:

Be it known that I, LE ROY A. CRUMLEY, a citizen of the United States, and a resident of the county of Bronx, city and State of New York, have invented a new, original, and ornamental Design for Lighting-Fixture Parts, of which the following is a specification, reference being had to the accompanying drawing, forming a part hereof.

Fig. 1 is an inverted plan view, wherein the portion indicated in full line outline is

ornamented in the same manner as the portion more fully illustrated, and

Fig. 2 is an elevation, with parts in section.

I claim:

The ornamental design for a lighting fixture part substantially as shown.

LE ROY A. CRUMLEY.
